COLLAPSIBLE BOAT

Malcolm N. Stanley, Newton, Mass.

Application March 20, 1950, Serial No. 150,779

5 Claims. (Cl. 9—2)

1

This invention relates to fabric covered boats of the type which may be collapsed or folded like an umbrella. The umbrella type collapsible boat involves a central mounting member to which are hinged ribs for stretching and shaping the fabric covering of the boat. Such a boat may be quickly expanded or collapsed without disassembly of the ribs and is therefore to be distinguished from collapsible kayaks or flatboats having several sections which must be interconnected in assembling the boat. Despite the quick folding properties of the umbrella type boat it is usually limited to a round shape in which the ribs are all of the same length. In contrast an elongate boat is safer to propel and easier to steer, and allows more room and comfort for the boatman. In addition the customary umbrella type construction involves a central staff extending from the aforesaid mounting member, the staff serving as a support for pivotally mounted braces for holding the ribs expanded. The staff and brace structure is complicated and cumbersome and is not conveniently adapted to an elongate construction. If the ribs of an umbrella type boat are lengthened to provide an elongate construction without lengthening the braces unequal stresses are placed on the braces. On the other hand if the braces are lengthened proportionally to the ribs the longer braces will oppose the shorter ribs during folding and will not allow the boat to be completely collapsed.

The objects of the present invention therefore are to provide an umbrella type of boat in which the usual staff and braces are eliminated, which is simple and rugged, and which is of an improved and compact construction, quickly and easily folded, and of simplified manufacture.

In a broad aspect the invention involves the combination of a mounting plate or like base member disposed centrally of the boat to which a plurality of radial ribs are pivotally attached so that they may be swung between a closed position in which the ends of the ribs come together and an open position in which the ends of the ribs are spaced and the aforesaid covering of the boat is expanded, the ribs being held in open position by a stiff stress plate bearing on the ribs intermediate their ends, means being provided for pressing the stress plate against the ribs and locking them in open position. Preferably the stress plate is downwardly concave so that its periphery bears on the ribs. If desired fluted portions may be formed at the periphery to fit against the ribs and prevent them from shifting when in open position.

2

In a further aspect an upright shaft is mounted on the base and the stress plate is provided with a central opening to receive the shaft therethrough, the aforesaid locking means engaging with the shaft above the plate and carrying bearing surfaces which press downwardly on the plate. In a specific aspect the shaft is provided with a slot or similar opening having a downwardly directed abutment and the cooperating locking means comprises a lever having a pivot member or element for engaging said abutment. In this embodiment the bearing surface of the lever is a cam surface for camming against the plate as the lever is moved about its pivot member thereby pressing the stress plate on the ribs.

In another aspect the stress plate is employed for mounting a chair and is provided with two pairs of slots disposed in a symmetrical four-cornered pattern. The chair has one pair of legs provided at their lower ends with an extension in the shape of a tongue and another pair of legs with hook elements and shoulder elements, the tongue elements being adapted to be inserted through one pair of slots while bearing on the stress plate, the hooked elements being adapted to be inserted through the outer pair of slots and to engage the under side of the plate while the shoulder elements bear on the upper side of the plate, the ends of the second pair of legs being spaced apart a different distance than the corresponding slots so that the legs must be sprung in order to insert the hooked elements into the slots, whereafter they will spring back to hold the hooks engaged.

In still another aspect the invention relates to a boat having tubular ribs with upturned portions at their outer ends, said portions being hollow to receive the pin of an oarlock, the fabric covering for the boat having a hem folded over the ends of the ribs and provided at the fold of the hem with a grommet for admitting the pin of an oarlock through the grommet to the hollow end of the tube. The oarlock comprises the aforesaid pin, the pin having a portion of reduced diameter, a U-shaped piece for holding the shaft of an oar, mediate the ends of the U-shaped piece an opening in which is firmly fitted the reduced portion of the pin, and a plate member interposed between the pin and the U-shaped piece and having a flat under surface for bearing on the grommet so that the U-shaped piece does not unduly wear the grommet or the fabric covering. A novel feature of this construction is that the oarlock is fabricated from bar stock and the pin is formed from cylindrical stock.

For the purpose of illustration a typical embodiment of the invention is shown in the accompanying drawings in which

Fig. 1 is a plan view of the boat parts being omitted;

Fig. 2 is a side elevation;

Fig. 3 is a perspective view showing the boat folded;

Fig. 4 is a section on line 4—4 of Fig. 1;

Fig. 5 is an enlarged detailed plan view;

Fig. 6 is an isometric view of a chair mounted on a stress plate;

Figs. 7 and 8 are fragmentary plan views;

Figs. 9 and 10 are fragmentary sectional views;

Fig. 11 is a detailed side elevation of a locking device;

Fig. 12 is a top view of a locking lever;

Fig. 13 is a sectional view of another locking device;

Fig. 14 is an enlarged plan view of a portion of Fig. 1; and

Figs. 15 and 16 are side elevations of an oarlock.

In the particular embodiment of the invention chosen for the purpose of illustration the boat comprises a waterproof canvas cover 1, ribs 2, a central mounting plate 3 for the ribs, an oval stress plate 4, a locking device 6, a seat 7 mounted on the stress plate, and oarlocks 8 fitting the ends of ribs 2. At the center of the bottom of the boat, both inside and outside, reinforcing canvas layers 9 are provided.

As shown in Figs. 4 and 5 the hollow tubes or ribs 2 are flattened at their inner ends and pivotally attached to spacers 10 mounted on the base 3 so as to extend radially from the base. The ribs are of different lengths and are curved upwardly at their outer ends to form a framework for the sides of the boat. The outer ends of the ribs engage in pockets 11 in a hem 18 at the upper edge of the canvas covering 1.

Near both ends of each of the ribs 2 a cork plug 81 is inserted to provide a water-tight seal for the air space between the plugs (Figs. 4 and 5). Tubing with an inside diameter of approximately 6/8 inches used in a boat approximately four by six feet, if so sealed, affords a buoyancy adequate to support a boatman should the boat swamp.

Extending upwardly from the middle of the base plate 3 and attached thereto is a shaft 11 formed of tubular stock and flattened for a substantial portion of its length. The flattened portion is provided with a vertical recess 15 along one side (Fig. 11). On the opposite side of the shaft are three horizontal notches 12 having widened interior ends for receiving and engaging the pivot pin 24 of a locking lever 6.

To hold the ribs in open position as shown in Figs. 1, 2 and 4 the stress plate 4 is placed on top of the ribs with the shaft passing through an unsymmetrical opening 21 complementary to the cross section of the shaft. As shown in Fig. 14 the plate can be fitted over the shaft only in one way. The plate is then pressed against the ribs and locked securely by means of the locking device 6 as shown in detail in Figs. 11 and 12. Around the periphery of the stress plate 4 are fluted portions matching the curve and relative angle of the ribs at that portion intermediate their ends which lies under the periphery of the stress plate. The fluted portions position the ribs and prevent them from shifting along the bottom of the boat. Preferably the stress plate is formed concave downward as shown in Figs. 2

and 4 and although the plate is relatively stiff it yields slightly when the locking device cooperating with the upright shaft 11 presses the plate against the ribs.

5 The embodiment of the locking device shown in Figs. 4, 11 and 12 comprises a lever having two parallel side plates 22 interconnected in spaced relation by rivets 23 and 24. The lever is generally L-shaped, one of the rivets being disposed at the corner of the L. The rivet 24 acts as the pivot point for the lever and engages one of the slots 12 of the shaft 11. Mounted at the end of each of the short branches of the L-shaped plate 22 are curved cam plates 26 normal to the planes of the side portions 22. The plates are cammed with reference to the pivot point 24. Thus, when the pivot point or rivet 24 is engaged in one of the slots 12 and the lever is moved about its pivot point the plates 26 cam the stress plate 4 downwardly on the ribs. The end of the long branch of the L-shaped plates has a short extension 27 directed generally in the same direction as the short branch of the L for holding the lever off the stress plate thus allowing a grip under the lever when the stress plate is clamped by the lever.

An alternate form of locking device is shown in Fig. 13 and comprises a modified upright shaft 11a attached to the base plate 3 and a plug 31 provided with a protective cap or hood 32. In this case the upright shaft 11a is threaded internally, the plug 31 having a corresponding external threaded portion 33. The plug is also provided with a threaded portion 34 of wider diameter at its upper end for affixing the cap 36. The cap has an inside diameter slightly larger than the outside diameter of the shaft 11a so that when the stress plate 4a, having a circular rather than an unsymmetrical opening at its center is fitted over the shaft 11a, the cap and plug assembly may be screwed down with the cap outside the shaft 11a and bearing on the stress plate. As the cap is screwed down it encloses the shaft 11a sealing and protecting the threaded portions of the shaft and the plug 31 and urges the stress plate downward against the ribs.

As previously mentioned the periphery of the fabric cover at the ends of the ribs is hemmed with folds which cover the ends of the ribs, and where it is desired to pass an oarlock pin into the end of the upturned hollow end of a rib a grommet is provided at the fold of the hem 18a, the grommet bearing on the ends of the ribs and interposed between the fabric and the end. An especially fabricated oarlock particularly suitable for use in combination with the grommet and the ends of the hollow ribs is shown in Figs. 15 and 16. The oarlock comprises the usual pin 41, a wear plate 42 and a U-shaped oar support 43. Preferably the oar support 43 is formed of bar stock, such as half-round stock, by bending the stock to proper shape. At the center of the U the support is provided with a circular hole 44 in which the reduced portion 47 of the pin 41 is press fitted or riveted. Since the outside of the lower portion of the curved oar support would unduly chafe the grommet a wear plate 42 is fixed between the pin and the support. The wear plate 42 is provided with an extension 49 having an opening 51 to which a retaining line 52 may be attached. The extension includes a curved portion 53 which slightly elevates the opening 51 above the grom-

met so that the knot of the line 52 will not rub on the fabric cover 1.

The stress plate is particularly adapted for mounting a folding chair 7 such as that shown in Figs. 1, 4 and 6. As shown in Fig. 1 the stress plate is provided with two pairs of slots 61 and 62 disposed in a four-cornered pattern, two of the slots 61 extending transversely of the boat and the other pair 62 disposed lengthwise of the boat. The legs of the chair 63 and 64 have at their ends attaching devices 66 and 67 adapted to fit in the slots 62 and 61 respectively. The rear legs 64, preferably formed of tubular stock, are flattened at their lower ends to form a tongue which is bent to lie parallel to the stress plate 4. A shoulder 69 is formed when the end is flattened. The ends of the forward legs 63 are flattened in a plane perpendicular to the stress plate 4 and a rectangular notch cut in the end of the flat portion 70. At each side of the notch two hooks 72 and 73 are then bent at right angles to each other and to the flat portion 70. In attaching the chair to the stress plate the tongues 68 of the rear legs 64 are inserted in the transverse slots 61 until the shoulders 69 bear on the surface of the stress plate. The hooks 73 of the forward legs are then inserted through the longitudinal slots 62 and engaged under the under surface of the plate with the hook or shoulder 72 bearing on the top of the plate. The longitudinal slots 62 are spaced apart a less distance than the flattened portions 70 so that the forward legs 63 must be sprung together in order to insert the hook 73 through the slot. The legs then spring apart and hold the hook 73 under the plate, thus locking the chair to the plate 4. While the attaching devices 66 and 67 are particularly designed for use with the stress plate 4 they may be used to attach chairs to any floor or deck provided with a plate or plates having slots 61 and 62.

It should be understood that the present disclosure is for the purpose of illustration only and that this invention includes all modifications and equivalents which fall within the scope of the appended claims.

I claim:

1. An elongate collapsible boat comprising a flexible skin and a framework for holding the skin collapsed or expanded, said framework comprising a central mounting member located interiorly of the skin, radiating from said member and pivotally attached thereto a plurality of ribs of different lengths movable between a closed position in which the skin is collapsed and an open position in which said skin is expanded, extending upwardly from the mounting member and attached thereto a shaft having a downwardly directed abutment, a stiff plate separate from the framework for storage in the collapsed boat and adapted to be disposed over said member and ribs for bearing on the ribs intermediate their ends to hold the ribs in open position, said plate having an opening admitting said shaft therethrough, engageable with the shaft above the plate a detachable lever having a pivot member for engaging said abutment and a cam surface spaced from said pivot member, said cam surface being disposed to swing about said pivot member to engage the plate and cam the plate against the ribs on movement of the lever about said pivot member, thereby to secure the ribs and skin in open position.

2. An elongate collapsible boat comprising a

flexible skin and a framework for holding the skin collapsed or expanded, said framework comprising a central mounting member located interiorly of the skin, radiating from said member and pivotally attached thereto a plurality of ribs of different lengths movable between a closed position in which the skin is collapsed and an open position in which said skin is expanded, extending upwardly from the mounting member and attached thereto a shaft having an unsymmetrical cross section portion, a stiff plate separate from the framework for storage in the collapsed boat and adapted to be disposed over said member and ribs for bearing on the ribs intermediate their ends to hold the ribs in open position, said plate having an opening complementary to said unsymmetrical cross section portion so that the plate can be fitted over the shaft in only one position, and engageable with the shaft above the plate detachable locking means having a bearing surface for pressing and locking the plate against the ribs, thereby to secure the ribs and skin in open position.

3. An elongate collapsible boat comprising a flexible skin and a framework for the skin, said framework comprising a central mounting member located interiorly of the skin, radiating from said member and pivotally attached thereto a plurality of ribs of different lengths movable between a closed position in which the skin is collapsed and an open position in which the skin is expanded, a shaft attached to and extending interiorly from the mounting member, a stiff plate separate from the framework for storage in the collapsed boat and adapted to be disposed over the mounting member and the ribs for bearing on the ribs to hold the ribs in open position, said plate having an opening admitting the shaft therethrough, and a detachable plate-locking device engaging the shaft, said device having a bearing surface for pressing on the plate and mechanical advantage means forcing said surface against the plate to urge the ribs to open position and secure the ribs and skin in open position.

4. An elongate collapsible boat comprising a flexible skin and a framework for the skin, said framework comprising a central mounting member located interiorly of the skin, radiating from said member and pivotally attached thereto a plurality of ribs movable between a closed position in which the skin is collapsed and an open position in which the skin is expanded, said ribs being longer lengthwise of the boat than crosswise, a shaft attached to and extending interiorly from the mounting member, a stiff plate separate from the framework for storage in the collapsed boat and adapted to be disposed over the mounting member and the ribs for bearing on the ribs to hold the ribs in open position, said plate having an opening admitting the shaft therethrough, and a detachable plate-locking device engaging the shaft, said device having a bearing surface for pressing on the plate and mechanical advantage means forcing said surface against the plate to urge the ribs to open position and secure the ribs and skin in open position, said plate being generally oval in shape so that its radius parallel to each rib is substantially proportional to the length of the rib, thereby to equalize the force on each rib.

5. An elongate collapsible boat comprising a flexible skin and a framework for the skin, said framework comprising a central mounting member located interiorly of the skin, radiating from

said member and pivotally attached thereto a plurality of ribs of different lengths movable between a closed position in which the skin is collapsed and an open position in which the skin is expanded, a shaft attached to and extending interiorly from the mounting member, a stiff plate separate from the framework for storage in the collapsed boat and adapted to be disposed over the mounting member and the ribs for bearing on the ribs to hold the ribs in open position, said plate having an opening admitting the shaft therethrough, a detachable plate-locking device engaging the shaft, said device having a bearing surface for pressing on the plate and mechanical advantage means forcing said surface against the plate to urge the ribs to open position and secure the ribs and skin in open position, and a plurality of pivot means attached to and extending above said mounting member, each of said ribs being attached to and slightly inclined downwardly from one of said pivot means adjacent the skin for a substantial part of their length when the skin is

in open position, and said plate being downwardly concave so as partially to curve over said pivot means on to said ribs.
